REPEATER FOR WEFT REPLENISHING
LOOMS

Benjamin W. Brouwer, Worcester, Mass., assignor
to Crompton & Knowles Loom Works, Worcester,
Mass., a corporation of Massachusetts

Application December 24, 1942, Serial No. 469,991

15 Claims. (Cl. 139—232)

This invention relates to improvements in weft replenishing looms and it is the general object of the invention to provide such a loom wherein a number of different stacks of reserve bobbins can be utilized for the replenishment of a single shuttle.

It has been proposed heretofore to employ repeaters or the like for the several stacks of a multi-color weft replenishing mechanism operative to permit bobbins to be drawn from more than one stack for the replenishment of a single shuttle, but as heretofore made such mechanisms have been restricted to three stacks because of the cam which positions the stack selector. The cam has various steps operatively connected to the stack selector and is given a step by step movement, usually by an actuator connected to the transfer mechanism. In the rotation of the cam it is necessary for the lever which cooperates with it to assume various angular positions depending upon the levels of the cam, but the cam will not take care of more than three stacks because shift from the high to the low level is so great as to interfere with the proper operation of the mechanism.

It is an important object of my present invention to provide a multi-stack bobbin magazine having a releaser for each stack and a control mechanism including a cam having fewer steps or levels than the number of stacks used, thereby permitting the construction of a simple cam which will permit the cam lever to move readily from high to low position.

In a form of multi-color weft replenishing mechanism which has gone into extensive use a magazine is used employing vertical slides to operate cradles for the several bobbin stacks, one slide and cradle for each stack. When it is desired to use the full capacity of a magazine having four stacks, for instance, to replenish a single shuttle, all of the stacks will carry weft of the same kind. According to another feature of my invention the stacks are arranged in pairs each of which corresponds to a step or level of the aforesaid cam. The vertical slides cooperate with a horizontally moving selector which in the usual multicolor weft replenishing mechanism has a separate position for each vertical slide, but as set forth hereinafter I provide mechanism by which the selector will have as many positions as there are pairs of stacks and these positions will be determined by the cam.

In order that the selector in any operating position may cooperate with the corresponding pair of slides, one slide at a time, each slide is pro-

vided with a pivoted pawl or the like, and the pawls of a pair move alternately into operative position with respect to the selector. By this arrangement first one and then the other of the stacks of a pair will feed bobbins to the shuttle without requiring movement of the selector, and the cam operates to move the selector from one pair to the other pair of slides. In this way the full capacity of the magazine can be used for replenishing a single shuttle by giving the selector half as many positions as the number of stacks employed.

It is a further object of my invention to provide an improved cradle releasing slide having a selector actuated lug pivoted thereon for movement into and out of operative position with respect to the selector. A spring mounted on the slide may be employed for urging the lug toward its operative position and other mechanism operated by the slides as they shift is used to determine whether the lugs shall be operatively or inoperatively positioned with respect to the selector. In this feature of my invention the selector may register with one pair of slides for 25 two successive transfers and then shift to register with the other pair for the next two successive transfers, or the selector can shift from one pair to another pair for each transferring operation of the loom. These two modes of operating the selector are possible because the movable lugs of any one pair shift to cause alternate operation of the slides of the pair whether or not the replenishing operations which operate the slides of any one pair are consecutive.

35 With these and other objects in view which will appear as the description proceeds, my invention resides in the combination and arrangement of parts hereinafter described and set forth.

In the accompanying drawings wherein I show 40 two forms of control for the selector mechanism,

Fig. 1 is a front elevation of a weft replenishing loom having my invention applied thereto,

Fig. 2 is a side elevation of the weft replenishing mechanism as seen from the center of the loom and showing the preferred form of control for the selector mechanism,

Fig. 3 is an enlarged vertical section on line 3—3 of Fig. 2,

Fig. 4 is a diagrammatic view showing two pairs of slides and the positioners for the pivoted lugs,

Fig. 5 is a horizontal detailed section on line 5—5 of Fig. 4,

cradle mechanisms on an enlarged scale looking in the direction of arrow 6, Fig. 1,

Fig. 7 is a detailed vertical section on line 7—7 of Fig. 2 showing a front elevation of the preferred form of selector control mechanism,

Fig. 8 is a diagrammatic view showing the relation between the cam used in the preferred form of the invention and the lever which controls the selector, and

Fig. 9 is a view similar to Fig. 8 showing a modified form of cam for the lever which positions the selector.

Referring particularly to Figs. 1 and 2, a loom frame 10 supports a lay 11 which is reciprocated backwardly and forwardly in the usual manner by means of connectors 12. In the present instance the left hand end of the loom is provided with a gang G of shuttle boxes the upper cell 14 of which will remain in active position to receive and have picked therefrom a shuttle S. Other shuttle boxes may be used to accommodate other shuttles which will not be replenished by the magazine but which can have their supplies renewed by hand. The invention is concerned primarily with the replenishment of shuttle S and the other shuttles not shown are not necessary and can be omitted. The upper left hand part of the loom may be provided with a pattern mechanism K of the Knowles type for operating the shuttle boxes by well-known means if more than one shuttle is used and also for raising or lowering the harnesses H. The right hand end of the lay as viewed in Fig. 1 is provided with a single shuttle box 15 to receive the shuttle S, and right and left picker sticks 16 and 17, respectively, operate to pick the shuttle alternately from the boxes, causing the shuttle to enter box 15 on alternate picks of the loom as the lay is advancing.

A multi-stack magazine M is located at the right hand end of the loom and in the present instance is provided with four stacks of reserve bobbins R', R2, R3 and R4, respectively, associated with vertical slides 20, 21, 22 and 23, respectively. Each slide is operatively connected at its lower end to a bobbin releasing cradle 25 one of which is shown in Fig. 6. The slides are normally down and their cradles empty and positioned as shown in Fig. 6 to support the bottom bobbin of the associated stack. When any slide is raised the cradle therefor rocks as indicated in Fig. 6 from the full to the dotted line position to permit the lowest bobbin of the superposed stack to move into the cradle, and when the slide is lowered the cradle is returned to normal position and the bobbin in it is released to move to the transfer position T shown in dot and dash lines in Fig. 6.

The magazine operates in conjunction with a weft detector D which determines the condition of weft in the shuttle while it is in box 15. When the weft is exhausted the detector operates well known control mechanism designated generally at 27 to lower rod 28 and cause rocking of a stack selector and slide actuator 29. The selector includes a shaft 30 slidable in fixed bearings on the magazine frame and having secured to the rear end thereof a grooved collar 31 which cooperates with the upper end of a lever 32 pivoted as at 33 to the magazine frame. As the selector rocks in a counter-clockwise direction as viewed in Fig. 1 incident to indication of weft exhaustion by the detector its actuating fingers 35 and 36 will rise to lift the vertical slide which happens at the time to register with one or another of the fingers.

The mechanism 27 is connected to a rod 38 which rises every second pick of the loom to lift the rod 28 and therefore give the selector a clockwise rotation as viewed in Fig. 1 when the shuttle is on the end of the lay opposite the magazine. In the accompanying down motion of the fingers 35 and 36 one of the latter will engage the depressing lug 39 of the previously raised slide and lower it.

In the usual multi-color weft replenishing loom the actuator 29 can slide longitudinally under control of the box mechanism after the detector has given an indication of weft exhaustion when the shuttle is on the left hand end of the loom as viewed in Fig. 1, but inasmuch as shuttle box 14 will ordinarily be in active position in the practice of my present invention, movements of the actuator 29 necessary to the accomplishment of my invention will not be effected by the box motion at the opposite end of the loom but by structure to be described hereinafter.

The lay is provided with a bunter 40 normally above a latch 41 connected to a transerrer arm 42 movable about fixed stud 43 on the magazine frame. When a transfer is to occur the magazine is set for a replenishing operation by downward movement of a rod 45 which as shown in Fig. 2 is connected to the latch 41. The magazine thus set for operation is caused to have its replenishing operation by the lay as the latter nears the forward part of its advancing movement and a bobbin in the dot and dash line position shown in Fig. 6 will be inserted into the shuttle in box 15.

Rod 45 is connected at its upper end to a lever 47 secured to a rocking shaft 48 mounted for oscillation in the upper part of the magazine frame. Shaft 48 carries a shelf 49 which is normally in raised position but is engageable for depression by dogs 50 on the upper ends of the slides 20—23. When any slide rises its dog will spring over the shelf, and when the slide is lowered as already described the dog will rock shaft 48 in the clockwise direction as viewed in Fig. 1 to lift a rod 51 connected to the shaft at its upper end and to a shuttle position detector 52 at its lower end. The detector 52 comprises a head 53 which is normally in forward position out of the path of the lay, but when the magazine is set for transfer by the oscillation of shaft 48 the head 53 will move rearwardly around pivot 54, and the advance movement of the lay on the transferring beat of the loom will act to return the head 53 to its forward position, and operate through downward movement of rod 51 to return the shelf 49 to its normal raised position.

It is believed that the operation of the mechanism thus far described will be understood from the foregoing description. Indication of weft exhaustion by the weft detector when the shuttle is under the magazine results in raising one or another of the slides 20, 21, 22 and 23 as will be described hereinafter, and after the shuttle has reached the other side of the loom rod 38 will act through mechanism 27 to cause down movement of the previously raised slide and effect oscillation of the shaft 48 so that the magazine will be set for transfer, this setting involving the lifting of latch 41 into the path of bunter 40, movement of the shuttle position detector head 53 rearwardly, and movement of a bobbin from one or another of the stacks to transfer position under the transerrer arm.

For further reference to the structure and mode of operation of the structure just described

reference may be had to the following patents: 1,030,748, 1,261,417 and 1,510,765.

An arm 60 extends upwardly from the trans-ferrer arm and is connected to a rod 61 the rear end of which is pivoted to a lever 62 carrying an actuator pawl 63 and mounted on a fixed stud 64. Also mounted on the stud is a ratchet wheel 65 fast with respect to a lock wheel 66 cooperat-ing with a yielding lock finger 67 pivoted on previously described stud 33. The ratchet and lock wheel are fixed with respect to a cam 68 shown in Fig. 8 having a high dwell 69 connected by inclines 70 to an intervening low dwell 71. The dwells and inclines of cam 68 engage a roll 72 on lever 32 to position the latter. The stroke of rod 61 is such as to cause approximately a one-fourth turn of the cam each time the trans-ferrer lever 42 descends during a replenishing operation, and four successive transfer movements will effect a complete rotation of the cam. In some respects the cam and means of actuating it from the trans-ferrer lever may be similar to structure shown in Gordon Patent No. 1,030,077, although as will be pointed out hereinafter the cam has a relation with respect to the replenishing mecha-nism different from that set forth in the last named patent.

The front pair of vertical slides 20 and 21 are provided with lifting lugs 80 and 81, respectively, operable by finger 35 on the selector, while the rear pair of slides 22 and 23 have their lugs 82 and 83 operable by the rear actuator finger 36. The front pair of slides have their depressing lugs 39 operated by finger 35, while lugs 39 of the rear slides 22 and 23 are operated by finger 36.

The upper or lifting lugs are constructed dif-ferently from those heretofore used in weft re-plenishing mechanisms. These lugs are made and mounted on their vertical slides in such man-ner that they can swing either into or out of reg-ister with their corresponding actuator fingers 35 and 36. Referring particularly to Figs. 4 and 5 the slides 21 and 22 are each provided with a lat-erally extending stud 85 which passes through the hollow hubs 86 of the corresponding lugs 81 and 82. A spring within each hollow hub has one end attached to the associated lug and the other end attached to a collar 88 held in fixed adjusted position on the stud. The effect of these springs is to lift the corresponding lugs to active position, the spring of slide 21 tending to turn lug 81 in a counter-clockwise direction to place lifter boss 91 in lifting position as viewed in Fig. 4. The spring corresponding to slide 22 tends to turn lug 82 in a clockwise direction as viewed in Fig. 4 to place lug 92 in lifting position. Suitable stops 95 and 96 on the slides are provided to limit the angular movement of the pivoted lugs.

The front and back vertical slides 20 and 23 carry laterally extending studs 97 similar to studs 85. Studs 97 extend through the solid hubs 98 of the associated lugs 80 and 83, and torsion springs 99 having one end thereof attached to the associated slide and the other end to the corresponding hub 98. Springs 99 tend to raise their lugs 80 and 83 so that boss 90 of lug 80 tends to turn clockwise toward operative position as viewed in Fig. 4, while boss 93 on the rear lug 83 is urged to turn in a counter-clockwise direction to its opera-tive position by its spring. Stops 100 and 101 limit the angular movements of lugs 80 and 83.

The movable lugs are positioned by controllers P' and P2 corresponding to the front and back pairs of vertical slides respectively. These con-trollers are alike and a description of one will suf-

fice for both. Controller P' comprises a lever 105 pivoted at 106 to the magazine frame and having an upwardly extending arm 107 pivotally connected as at 108 to a spring plunger 109. The 5 plunger extends through a guide 110 fastened to the magazine frame and is surrounded by a spring 111 which exerts a downward force on the pivot 108. Lever 105 has front and back wings 112 and 113, respectively, located for engagement with the vertical slides 20 and 21, respectively. Thus, as seen at the right of Fig. 4, when slide 20 is raised by the selector it will engage wing 112 to rock lever 105 in a counter-clockwise direction to move the pivot 108 to the left in which position it is resiliently held by spring 111. When slide 21 15 rises, however, it engages wing 113 to rock the lever 105 in the opposite direction and move the pivot 108 to the right in which position it will also be held resiliently by the spring 111. A similar 20 relation exists for the controller P2 relatively to the rear pair of slides, the lever 105 of controller P2 being rocked to the left when slide 22 rises and to the right when slide 23 rises.

The levers 105 of controllers P' and P2 have 25 depending therefrom lug positioners 120 and 121, respectively, which may be of flat form as indicated in Fig. 5 and are preferably made of resil-ient material. The lower end of positioner 120 is capable of engaging lugs 80 and 81, while posi-tioner 121 engages lugs 82 and 83, as shown in 30 Fig. 5. When positioner 120 shifts to the right as shown in Fig. 5 it will rock lug 80 downwardly to inactive position and permit lug 81 to be moved to active position by its spring, and when moving 35 to the left positioner 120 will depress lug 81 to idle position and permit lug 80 to become active. A similar control is exerted over lugs 82 and 83 by positioner 121. Each of the pivoted lifter lugs has a rounded surface 122 which engages the cor-40 responding positioner below a horizontal line passing through the associated pivot to assist the positioner in turning the lugs on their centers. The bosses 90-93 are substantially over their 45 respective lugs 39 when in active position but are out of vertical alignment with these lugs when in inactive position.

In operation, it may be assumed that the parts are in the position shown in Figs. 2, 4, and 5 and that the shuttle is being picked back and forth in customary manner with a sufficient supply of weft. Eventually this supply becomes depleted and the detector initiates a replenishing opera-tion by causing upward movement of actuator 50 fingers 35 and 36. It may be assumed for pur-poses of description that positioner 120 is in its right hand position and that selector 29 is in forward position with the finger 35 over the front pair of depressor lugs 39 and under boss 91, while the rear finger 36 is forward of and out of reg-ister with rear lugs 39 and pivoted lugs 82 and 83. Lugs 80 and 82 are idle and lugs 81 and 83 are in their active position. As finger 35 rises it will lift slide 21 and cause the latter as it approaches the upper end of its movement to engage wing 55 113 to rock controller P' in a clockwise direction, Fig. 4, from the full to the dotted line position. Positioner 120 is therefore urged to move rear-wardly, or to the left in Fig. 4, against boss 91, but the latter is momentarily held raised due to the fact that finger 35 is up. As soon as finger 35 moves downwardly away from boss 91 spring 60 109 and positioner 120 will cooperate to cause the pivoted lug 81 to move in a clockwise direc-tion to idle position. At the same time the piv-65 oted lug 80 rises to active position. Slide 21 re-

mains up and there is a bobbin in the corresponding cradle.

The operation just described initiates a replenishing operation of the loom and occurs while the shuttle is under the magazine. The shuttle is then picked on the opposite end of the loom and actuator finger 35 will be depressed as already described to engage the lug 39 of raised slide 21. Descent of slide 21 to its normal down position sets the magazine for transfer with the following results: the bobbin drawn from reserve stack R2 moves to transfer position, latch 41 rises to transfer position in the path of bunter 40, and shuttle position detector head 53 moves rearwardly. On the forward beat of the lay which occurs when the shuttle is next at the magazine end of the loom the lay bunter will engage the latch 41 to cause a transfer operation during which the transerrer arm 42 descends to insert the released bobbin into the shuttle and also cause rod 61 to move rearwardly. The cam 68 is thereupon given a $\frac{1}{4}$ turn and roll 72 moves from the low dwell 71 which it previously engaged up one of the inclines 70 to high dwell 69. At this time rod 38 descends as it always does when the shuttle is at the magazine end of the loom, but the weft detector is temporarily disabled in the usual manner and the selector 29 therefore cannot rock, hence it slides rearwardly without interfering with any of the vertical slides. During the last part of the forward motion of the lay the latter moves head 53 forwardly to reset the magazine.

Rearward movement of selector 29 places finger 36 in register with boss 93 and over the lugs 39 of slides 22 and 23, while at the same time moving finger 35 rearwardly out of register with lugs of the front pair of slides.

The parts remain in this position with the selector rearward until the shuttle is again depleted, whereupon the previously described operation is repeated and finger 36 is raised to engage boss 93 and lift the slide 23. The controller P2 is thereupon caused to rock in a clockwise direction as viewed in Fig. 4 and the positioner 121 shifts to the left. The shuttle is then picked to the opposite end of the loom and slide 23 is depressed by finger 36. During the second transfer operation which follows arrival of the shuttle at the magazine end of the loom, cam 68 will again be given a one-quarter turn, but due to the length of dwell 69 the roll 72 will remain in contact with it and the selector 29 will therefore remain in rear position. The fingers 35 and 36 remain as they were at the end of the first transfer, but lug 93 is now idle and lug 92 active.

For the third replenishing operation lug 92 will be engaged by finger 36 as the lay rises and slide 22 will therefore move up to advance a bobbin in stack R3 toward transfer and at the same time rock positioner P2 back to the position shown in Fig. 4. Subsequent depression of lug 39 on slide 22 by finger 36 will release the previously advanced bobbin of stack R3 so that it can move to transfer position and the loom will again be set for transfer. The ensuing movement of the transerrer arm 42 will give cam 68 another one-quarter turn, and this time roll 72 will move down one of the inclines 70 to the adjacent part of low dwell 71 and selector 29 will move forwardly.

For the fourth transfer slide 20 will be raised to return positioner P1 to the full line position of Fig. 4 and cam 68 will be given another one-quarter turn and cause low dwell 71 to move under roll 72 to the same position it occupied at

the beginning of the four transferring operations which have been described. The selector remains in forward position and the parts are placed so as to start the sequence just described when the fifth transfer is called.

In this cycle it will be seen that a bobbin is drawn from each of the reserve stacks in the order R2, R4, R3 and R1, even though the selector 29 is given only two longitudinal positions. In this preferred form of the invention it will be noted that the color slide moves only every second transfer.

The invention is not limited to the form of cam already described nor is it necessary that the selector slide 29 be moved longitudinally only every second transfer. The selector can if desired be moved longitudinally for each transfer, in which case a modified form of control cam 125 will be used as shown in Fig. 9. This cam has three spaced high dwells 126 and three intervening low dwells 127. Rigid with the cam is a six-toothed ratchet wheel 130 which is driven by a pawl 131 on a lever 132 rotating about the stud 64. Rod 133 connected to the arm 132 extends forwardly to be pivoted to an arm 134 on the transerrer 42. Arm 134 is shorter than arm 60, inasmuch as the cam in the modified form is shown as requiring six step-by-step movements for a complete rotation.

When cam 125 is used the selector 29 will be shifted for every replenishing operation of the loom, being in forward position on alternate transfers when the roll 72 engages low dwells 127 and being in rear position on intervening transfers when the roll engages the high points 126. Four successive step by step movements of the cam 125 will complete a cycle of operations of the magazine and an order in which bobbins could be drawn for transfer, for instance, would be stacks R1, R3, R2 and R4. In this sequence it will be noted that one bobbin is drawn from each of the four stacks. As in the preferred form it will be seen that the pivoted lugs perform half of the selecting operations while the selector 29 performs the remaining half of the selecting operations due to its shifting movements.

It is obvious that I am not limited to the two forms of cam set forth herein inasmuch as it is sufficient for the purpose of my invention if over 50 a large number of successive transfers the selector be forward for one-half of the transfers and be rearward for the other half of the transfers. Two successive rockings of the selector 29 about its axis when in the same longitudinal position will result in drawing a bobbin from each of the pair of stacks corresponding to that position. These successive rockings of the selector can occur either with or without an interfering longitudinal movement to the other position.

From the foregoing it will be seen that I have provided means by which a plurality of stacks of similar reserve bobbins can be utilized for the replenishment of a single shuttle by mechanism which draws the bobbins in rotation from the stacks but requires only half as many longitudinal positions for the selector as the number of stacks involved. This result grows out of the fact that the pivoted lugs effect part of the selection and the movement of the selector effects the remainder of the selection. It will also be seen that the selector can either be moved longitudinally for every transfer or for every other transfer. It will also be seen that I have provided an improved vertical cradle controlling slide having

pivoted thereto a lifter lug resiliently held in active position but movable to inactive position.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom operating with a shuttle and having weft replenishing mechanism to replenish the weft in the shuttle by bobbins drawn one at a time from any one of a plurality of stacks of similar reserve bobbins arranged in a plurality of pairs of stacks, a bobbin releaser for each stack, an actuator common to the releasers, means effective incident to an operation of the replenishing mechanism to move the actuator from one operating position corresponding to the pair of releasers of one pair of stacks to another operating position corresponding to the pair of releasers of another pair of stacks, and a releaser selector mechanism for each pair of releasers causing the actuator to operate the releasers of either pair of releasers one at a time and alternately for successive operations of said actuator when the latter is in the corresponding operating position.

2. In a weft replenishing loom operating with a shuttle and having weft replenishing mechanism to replenish the weft in the shuttle by bobbins drawn one at a time from any one of a plurality of stacks of similar reserve bobbins arranged in a plurality of pairs of stacks, a pair of bobbin releasers for each pair of stacks, one releaser for each stack, an actuator mechanism common to said releasers, means effective incident to operation of the replenishing mechanism to position said actuator mechanism operatively with respect to said pairs of releasers, one pair only at a time, means effective upon depletion of weft in said shuttle causing said actuator mechanism to operate whichever releaser registers therewith of the pair of releasers with respect to which the actuator mechanism is operatively positioned, and a selector means for each pair of bobbin releasers, the selector means of any given pair of bobbin releasers causing the actuator mechanism to operate alternately the releasers of said given pair of releasers for successive depletions of the shuttle which occur when said actuator mechanism is operatively positioned with respect to said given pair of releasers.

3. In a weft replenishing loom operating with a shuttle and having weft replenishing mechanism to replenish the weft in the shuttle by bobbins drawn one at a time from any one of a plurality of stacks of similar reserve bobbins arranged in a plurality of pairs of stacks, a pair of bobbin releasers for each pair of stacks, one releaser for each stack, an actuator mechanism for said releasers, means operative incident to an operation of said replenishing mechanism to position said actuator mechanism operatively with respect to said pairs of releasers, one pair at a time, means effective upon depletion of weft in the shuttle to cause said actuator mechanism to move in a given direction to operate whichever releaser registers therewith of the pair of releasers with respect to which said mechanism is operatively positioned, and a selector means for each pair of bobbin releasers, the selector means of any given pair of releasers being operated by one of the releasers of said given pair of releasers and causing the other releaser of the latter pair of releasers to be operated by the actuator mech-

anism when the latter has its next movement in said given direction while in register with said given pair of releasers.

4. In a weft replenishing loom operating with a shuttle and having weft replenishing mechanism to replenish the weft in the shuttle by bobbins drawn one at a time from any one of a plurality of stacks of similar reserve bobbins arranged in a plurality of pairs of stacks, a pair of bobbin releasers for each pair of stacks, one releaser for each stack, an actuator mechanism for said releasers, means operative incident to an operation of said replenishing mechanism to position said actuator mechanism operatively with respect to said pairs of releasers, one pair at a time, means effective upon depletion of weft in the shuttle to cause said actuator mechanism to move in a given direction to operate whichever releaser registers therewith of the pair of releasers with respect to which said actuator mechanism is operatively positioned, and a selector means for each pair of bobbin releasers, the selector means of any given pair of bobbin releasers being operated by the releasers of said given pair of releasers and causing said actuator mechanism to cooperate alternately and one at a time with the releasers of said given pair of releasers when the actuator mechanism has successive movements in said given direction with respect to said given pair of releasers.
5. In a weft replenishing loom operating with a shuttle and having weft replenishing mechanism to replenish the weft in the shuttle by bobbins drawn one at a time from any one of a plurality of stacks of similar reserve bobbins arranged in a plurality of pairs of stacks, a bobbin releaser for each stack, an actuator common to all the releasers, transfer mechanism to transfer a bobbin released from any one of said stacks into said shuttle, a positioner for said actuator controlled by said transfer mechanism and effective to locate said actuator operatively with respect to the pairs of releasers, one pair at a time, said positioner being caused by operation of the transfer mechanism to effect movement of the actuator from operative position with respect to one pair of releasers to operative position with respect to another pair of releasers, and a releaser selector mechanism for each pair of releasers causing the actuator to operate the releasers of its respective pair one at a time and alternately for successive operations of said actuator when the latter is in the corresponding operative position.
6. In a weft replenishing loom operating with a shuttle and having weft replenishing mechanism to replenish the weft in the shuttle by bobbins drawn one at a time from any one of a plurality of stacks of similar reserve bobbins arranged in a plurality of pairs of stacks, a pair of bobbin releasers for each pair of stacks, one releaser for each stack, an actuator mechanism for said releasers, a transerrer arm having an operating motion for each replenishing operation of the loom, a positioner for said actuator mechanism actuated by the transerrer arm and effective to locate said actuator mechanism operatively with respect to said pairs of releasers, one pair at a time, means effective upon depletion of weft in the shuttle to cause said actuator mechanism to move in a given direction to operate whichever releaser registers therewith of the pair of releasers with respect to which said actuator mechanism is operatively positioned, and a selector means for each pair of bobbin releasers,

any given selector means being operated by either one of the releasers of the associated pair of releasers and causing the other releaser of the latter pair of releasers to be operated by the actuator mechanism when the latter has its next movement in said given direction and is also registered with the pair of releasers associated with said given selector means.

7. In a weft replenishing loom operating with a shuttle and having weft replenishing mechanism to replenish the weft in the shuttle by bobbins drawn one at a time from any one of a plurality of stacks of similar reserve bobbins arranged in two pairs of stacks, a bobbin releaser for each stack, an actuator common to the releasers, a positioner controlling the position of the actuator, a member having a movement for each replenishing operation of the loom, means operated by the member causing the positioner to locate the actuator in two different positions in one of which the actuator is operatively positioned with respect to one of said pairs of releasers and in the other of which positions said actuator is operatively positioned with respect to the other of said pair of releasers, and a releaser selector mechanism for each pair of releasers, each releaser selector mechanism effective to cause the actuator to operate the releasers of the corresponding pair of releasers one at a time and alternately for successive operations of said actuator when the latter is in the same position with respect to said pairs of releasers.

8. In a weft replenishing loom operating with a shuttle and having weft replenishing mechanism to replenish the weft in the shuttle by bobbins drawn one at a time from any one of a plurality of stacks of similar reserve bobbins arranged in two pairs of stacks, a bobbin releaser for each stack, an actuator common to the releasers, a cam having high and low dwells to position the actuator, means operative incident to a replenishing operation of the loom moving said cam to make said dwells alternately operative to position the actuator and cause said high dwell to position the actuator operatively with respect to one only of said pairs of releasers and cause said low dwell to position the actuator operatively with respect to the other pair only of said pair of releasers, and a releaser selector mechanism for each pair of releasers, one of said releaser selector mechanisms causing the actuator to operate the releasers of one pair of releasers one at a time and alternately for successive operations of said actuator when the latter is operatively related to said high dwell and the other releaser selector mechanism causing the actuator to operate the releasers of the other pair of releasers one at a time and alternately for successive operations of said actuator when the latter is operatively related to said low dwell.

9. In a weft replenishing loom operating with a shuttle and having a weft replenishing mechanism to replenish the weft in the shuttle by bobbins drawn one at a time from a plurality of stacks of similar reserve bobbins arranged in two pairs of stacks, a pair of bobbin releasers for each pair of stacks, one releaser for each stack, an actuator common to the releasers, a cam having a high dwell corresponding to one of said pair of releasers and a low dwell corresponding to the other pair of releasers, a member having a movement incident to each replenishing operation of the loom and operatively connected to said cam to move said dwells alternately into positioning relationship with respect to said actuator, the

dwells of the cam being so constructed that the high dwell is in positioning relationship with respect to the actuator for two successive replenishing operations of the loom and then the low dwell is in positioning relationship with respect to the actuator for the next two successive replenishing operations of the loom, the high dwell effective to position the actuator operatively with respect to one pair only of the releasers and the low dwell effective to position the actuator operatively with respect to the other pair only of said releasers, and a selector mechanism for each pair of bobbin releasers, any given selector mechanism causing the actuator to operate the releasers of the associated pair of releasers one at a time and alternately for successive operations of said actuator when the latter is operatively positioned with respect to the pair of releasers associated with said given selector mechanism.

10. In a weft replenishing loom operating with a shuttle and having a weft replenishing mechanism to replenish the weft in the shuttle by bobbins drawn one at a time from any one of a plurality of stacks of similar reserve bobbins which are arranged in two pairs of stacks, a bobbin releaser for each stack, an actuator common to the releasers, a cam having alternating high and low dwells, a member having a movement incident to each replenishing operation of the loom operatively connected to the cam to cause a high dwell and a low dwell to become alternately active with respect to the actuator to position the latter for successive replenishing operations and effective to locate the actuator operatively with respect to one pair of releasers when the high dwell is active and locate the actuator operatively with respect to the other pair of releasers when the low dwell is active, and a releaser selector mechanism for each pair of releasers causing the actuator to operate the releasers of the corresponding pair of releasers one at a time and alternately for successive operations of said actuator, which occur when said actuator is operatively positioned by said cam with respect to said corresponding pair of releasers.

11. In a weft replenishing loom bobbin cradle controlling slide having an elongated body provided with a dog pivoted to the upper end thereof, a depressing lug fixed with respect to said body and located below said dog when the slide is in normal upright position, a lifting lug movably mounted on said slide intermediate said dog and said depressing lug, and resilient means on the slide tending to hold said lifting lug in normal operating position, said lifting lug being movable with respect to said body against the action of said resilient means away from said normal operating position.

12. In a weft replenishing loom bobbin cradle controlling slide having an elongated body provided with a dog pivoted to the upper end thereof, a depressing lug integral with said body and extending laterally from the latter below said dog when the slide is upright, a lifting lug pivoted to said body intermediate said dog and said depressing lug, said lifting lug being movable angularly with respect to the body from an active position substantially in vertical alignment with the depressing lug when said body is upright to an idle position out of vertical alignment with said depressing lug, resilient means tending to hold said lifting lug in active position, and stop means on said body engaging said lifting lug and cooperat-

ing with said resilient means to hold said lifting lug in normally active position.

13. A bobbin cradle controlling slide for a weft replenishing mechanism, said slide having an elongated body, a lug fixed to said body and offset therefrom and located in a line parallel to the length of said slide, a second lug pivoted to said slide and movable angularly thereon into and out of said line, resilient means on said slide tending to move said second lug into said line, and stop means on said slide to limit angular movement of said second lug relatively to said body.

14. In a weft replenishing loom bobbin cradle operating slide to cooperate with a lifting and depressing finger and having an elongated body provided with a dog pivoted to the upper end thereof when said slide is held upright, a depressing lug on said body for engagement with said finger and extending laterally therefrom below said dog when the slide is upright, a lifting lug between said dog and said depressing lug, a pivotal connection between said body and said lifting lug by means of which the latter is movable with respect to said body from one position to another position, said lifting lugs in one of said positions being placed for engagement with said finger, and a spring supported by said slide and tending nor-

mally to hold said lifting lug in one of said positions but permitting movement of said lifting lug to the other of said positions.

15. In a weft replenishing loom operating with a shuttle the weft of which is replenished by reserve bobbins drawn from any one of four stacks of similar reserve bobbins arranged in two pairs of stacks, a pair of bobbin releasers for each pair of stacks, one releaser for each stack, an actuator for the releasers capable of occupying two operating positions, one position for each pair of releasers, a positioner for the actuator effective to cause the latter to shift from the operating position corresponding to one of said pairs of releasers to the operating position corresponding to the other pair of releasers, and a single controller for each pair of releasers, each controller causing the releasers of the associated pair of releasers to release bobbins successively and alternately from the two individual stacks forming the associated pair, to the end that four successive operations of the actuator, two operations for each operating position thereof, will effect release of a bobbin from each of said four stacks for replenishment of said shuttle.

BENJAMIN W. BROUWER.
